WASTE AND OVERFLOW FOR BATHTUBS AND BASINS

Filed May 21, 1936

UNITED STATES PATENT OFFICE

2,063,399

WASTE AND OVERFLOW FOR BATHTUBS
AND BASINS

Floyd H. Rasmussen, Waterbury, Conn.

Application May 21, 1936, Serial No. 80,944

3 Claims. (Cl. 4—203)

This invention relates to an improvement in overflows for bathtubs and basins, and particularly to that type which include a vertically-movable plug into the waste-pipe and overflow 5 with means adjacent the overflow for operating the plug.

The object of this invention is to provide simple means by which the plug may be readily opened or closed, and to provide means for preventing waste water from entering a tube 10 through which a flexible shaft for operating the plug extends, and the invention consists in means for accomplishing these purposes and other details of construction as will be herein- 15 after described and particularly recited in the claims.

In the accompanying drawing:

Fig. 1 is a side view partly in section, illustrating a waste-and-overflow for bathtubs and basins, constructed in accordance with my invention; and

Fig. 2 is a sectional detail view of the waste-plug on an enlarged scale, showing the plug in its raised or open position.

In carrying out my invention, I employ a usual bushing 10 mounted in the waste-opening 11 of a bathtub 12 or wash basin. The tub or basin is also provided near its upper edge with the usual overflow-opening 13 through which overflow water may pass into an overflow-head 14 connected by a pipe 15 with a T 16 and a usual fitting 17 which is connected by a horizontal pipe 18 with the T 16.

Mounted in the bottom of the fitting is a short tube 19 having a contracted opening 20 and sitting over this tube is a stem 21 of a plug 22. Preferably, the hole 23 through which the sleeve of the plug extends will be formed on one side with a notch 24, and the stem 21 is formed at its lower end with an outwardly-projecting lug 25 which will pass through the notch 24 when turned into alignment therewith, and then, when the plug is turned, will prevent the plug's being withdrawn. As an additional safety 45 against the removal of the plug, the bushing 10 will be formed with upturned ears 26 to which a cap 27 may be attached.

The overflow-head 14 is formed at its rear with an opening 28 in which is mounted a tube 29 which projects toward the opening 13, and the tubes 29 and 19 are connected by pipes 30 and 31 which are connected together by an adjustable coupling 32, and extending through the tubes and pipes is a flexible shaft 33, its lower or operative end being provided with a

tapered valve 34 which, when raised, will close the opening 20 in the tube 19. The upper end 35 of the flexible shaft 33 is connected with a handle 36 which is sleeved over the tube 29 so as to be guided thereby, and this handle passes 5 through the usual strainer 37 which covers the overflow-opening 13.

In Fig. 1 of the drawing, the plug is shown in its closed position and the operating-handle 36 drawn outward. When it is desired to open 10 the plug, the handle will be pushed inward, as shown in broken lines in Fig. 1, which will move the flexible shaft so as to lift the plug from its seat to the position shown in Fig. 2. When so lifted, it will be noted that the opening 20 in 15 the top of the tube 19 will be closed, so that no water can get into this tube so as to corrode the flexible shaft. It will thus be seen that means for operating a waste-plug is provided, and the shaft for operating the same is so 20 housed that no water comes in contact with it, thus adding to the sanitary qualities of the fixture.

I claim:

1. A waste-and-overflow fixture comprising, a 25 bushing in the waste, a plug seated therein, said plug having a tubular stem, a fitting into which the waste opens, a vertically-arranged tube mounted in said fitting and over which the plug-stem extends, a flexible shaft extending from 30 the overflow into the waste-fitting, said shaft provided with a tapered stem adapted when raised to close the tube through which it projects, and means attached to the upper end of the flexible shaft for moving the same, whereby 35 the plug may be lifted from its seat.

2. A waste-and-overflow fixture comprising, a bushing mounted in the waste, a plug adapted to close the upper end of said bushing, said plug formed with a tubular stem provided at its lower 40 end with a finger, the bushing formed with a central opening for the passage of the plug-stem and a notch at one side of said opening through which the said finger may pass, a flexible shaft extending from the overflow into engagement 45 with the plug, said shaft provided with a tapered stem adapted to close the opening into the tube when the plug is in its raised position.

3. A waste-and-overflow fixture comprising, a 50 bushing in the waste, a plug seated therein, said plug having a tubular stem, a fitting into which the waste opens, a vertically-arranged tube mounted in said fitting and over which the plug-stem extends, a flexible shaft extending from 55

the overflow into the waste-fitting, said shaft provided with a tapered stem adapted when raised to close the tube through which it projects, a tube mounted in the overflow-head 5 through which the flexible shaft extends, and a handle telescopically movable on said tube and

interlocked with the end of the flexible-shaft, whereby inward and outward movement of the handle will correspondingly move the flexible shaft to open the waste-plug or permit it to close.
